UNITED STATES PATENT OFFICE.

JAMES MARSDEN, OF WIGAN, ENGLAND.

DESIGN FOR A PATTERN-CHART.

SPECIFICATION forming part of Design No. 29,197, dated August 9, 1898.

Application filed June 8, 1898. Serial No. 682,954. Term of patent 14 years.

To all whom it may concern:

Be it known that I, JAMES MARSDEN, a subject of the Queen of Great Britain and Ireland, and a resident of Wigan, in the county of 5 Lancaster, England, have invented and produced a new and original Design for a Pattern-Chart, of which the following is a specification, reference being had to the accompanying drawing, forming a part thereof.

o The drawing is a plan view of a pattern-chart, showing my new design.

As shown in the drawing, the leading or material feature of my design consists in a pattern-chart having represented thereon the 5 novel arrangement of patterns for a lady's jacket, as now described. At one side of one end of the pattern-chart is shown the fore part A, having inlays *a* at the sides and top of the shoulder, a dart *b*, a hip part *c*, a waist *d*, and a bust *e*. At the other side of this end is the fore part B, part *b'*, the back C, having

inlay *c'* and vent *c''*, a flap D, and a pocket E. Above the fore part A is the outside collar G, and above the fore-part facing is the inside collar F. The other end of the pattern-chart 25 shows the top side sleeve H, having button-stand *h* and under side sleeve I, the front side body J, the back side body K, having inlay *k*, and a pocket L.

Having thus described my invention, the 30 following is what I claim as new therein and desire to secure by Letters Patent:

The design for a pattern-chart substantially as herein shown and described.

In witness whereof I have hereunto signed 35 my name, this 12th day of May, 1898, in the presence of two subscribing witnesses.

JAMES MARSDEN.
